UNITED STATES PATENT OFFICE.

RICHARD WHITAKER, OF NEW BRUNSWICK, NEW JERSEY, ASSIGNOR, BY DIRECT AND MESNE ASSIGNMENTS, TO BRUNSWICK REFRIGERATING COMPANY, A CORPORATION OF NEW JERSEY.

VALVE FOR GAS-PUMPS.

No. 866,832.

Specification of Letters Patent.

Patented Sept. 24, 1907.

Original application filed January 11, 1904, Serial No. 188,612. Divided and this application filed January 5, 1905.
Serial No. 239,724.

To all whom it may concern:

Be it known that I, RICHARD WHITAKER, a citizen of the United States, residing at New Brunswick, in the county of Middlesex and State of New Jersey, have 5 invented certain new and useful Improvements in Valves for Gas-Pumps, of which the following is a specification.

This invention relates to improvements in valves for pumps used in compressing gas, such as ammonia gas 10 in ice-making machines, and is a division of an application filed by me January 11th, 1904, Serial No. 188,612.

The object I have in view is the production of a valve which is of the balanced type and double, that is to say, the outlet valve being of larger size and carrying 15 within it the inlet valve, ports being provided to admit the compressed gas to both sides of the outlet valve, it will be balanced and the actuating spring will not have to be excessively powerful. Another object is the production of a valve which may be very accessible, 20 and may be readily taken apart. I attain these objects by the mechanism illustrated in the accompanying drawings, in which

Figure 1 is a vertical section of a portion of a pump similar to that disclosed in my original application 25 above referred to, and showing the valve in section; and Fig. 2 is a sectional view thereof taken on the line 2—2 of Fig. 1, and Fig. 3 is a detail view.

In all of the views like parts are designated by the same reference characters.

30 In the drawings, the cylinder 1 is shown provided with an integrally formed water jacket 2 and a ground upper face 3. Upon the upper face 3 is a valve support or guide 4 having a ground upper face upon which rests a valve cap or crown 5. Secured to the upper part 35 of the cap 5 is an inlet pipe 6 which serves as a means for admitting gas to the cap. These parts are firmly secured together and to the cylinder casing by means of a tie bar 7 which surrounds the gas inlet pipe 6 and through which pass two or more tie bolts, 7^a, their lower 40 ends being firmly secured to the casing 7^b and their upper extremities being provided with nuts 7^c, so that tension may be imparted to the tie bolts and the tie bar may be drawn down to the cap 5, the valve guide 4 and cylinder 1 all being firmly locked in place as described 45 in my original application. The tie bar 7 resting upon the center of the cap 5 which is spherically shaped as shown, admits of tight joints being secured at all points, even if one of the nuts be set up tighter than the other. By removing the nuts and tie bar, parts which constitute 50 the upper portion of the pump may be separated and the valve reached for examination or repair.

The valve is balanced and duplex. That is to say,

it is balanced against pressure and is double, the outlet valve carrying the inlet valve within it. The outlet valve 8 is provided with a hollow rod 9, which works 55 within the valve guide 4, a tight joint being secured by means of the rings 10 and gland 11. Above the valve 8 is an equilibrium chamber 12, in which gas under cylinder pressure is admitted through the ports 13 (see Fig. 2), the valve guide 4 serving as a cover plate for the 60 chamber and constituting one of its walls. A spiral spring 14 is used to seat the valve. The gas at cylinder pressure being admitted to the chamber 12 when the valve 8 is raised by the pressure of the gas in the cylinder on the pressure stroke of the piston, will exert a 65 downward pressure on the valve to assist the action of the spring 14, such pressure being determined by the difference in area between the lower and upper faces of the valve. This difference of area may be proportioned by varying the diameter of the hollow rod 9 of 70 the valve.

The hollow rod of the outlet valve is of small size 75 relatively to the size of the seat with which the outlet valve engages, so that the area of surface of the outlet valve within the equilibrium chamber subjected to pressure in the direction which tends to seat the valve will be large relatively to the area of surface within the cylinder tending to unseat the valve.

The inlet valve 15 is of the shape shown, and engages 80 with a seat formed upon the valve 8. The inlet valve is provided with a long stem 16, which passes through the hollow rod 9 of the valve 8. The stem 16 is hollow and communicates with the chamber 17, which in turn communicates with the gas inlet pipe 6. A free passage for the entering gas through the valve 15 is secured 85 by means of the small lateral openings 18, which communicate with the annular passage 19 above the valve seat. The inlet valve is held upon its seat by means of a spiral spring 20, which rests upon a shoulder 21, formed within the hollow rod 9 of the valve 8. The 90 nut 22 limits vertical movement of the inlet valve, and serves as a means of adjustment of the tension of the spring 20. The gas pipe 23 communicates with the annular chamber 24 formed in the lower face of the outlet valve and above the seat thereof and serves to 95 draw off the compressed gas. This valve is extremely simple, and has but one packing, viz., the rings 10 and gland 11. Its operation is as follows: Upon the descent of the piston, the valve 15 is opened by the in-rushing gas, and upon the ascent of the piston the gas is compressed between the piston and the two valves. Upon the pressure within the cylinder exceeding that of the spring 14, the outlet valve will open sufficiently against 100 the tension of the spring to permit the gas under cylinder

der pressure to pass through the ports 13 to the equilibrium chamber 12. When the gas within the cylinder is compressed to such a degree that the downward pressure upon the outlet valve within the equilibrium chamber added to the tension of the spring 14, is insufficient to seat the valve, the latter will remain unseated, consequently upon the downward stroke of the piston, no gas will be drawn in through the inlet valve. This is for the reason that the inlet valve cannot open until 10. the outlet valve is seated, and the piston has descended far enough to produce a sufficient rarefaction of gas within the cylinder to cause an opening of the inlet valve against the tension of its closing spring. This will be understood from the following explanation: The 15 inlet valve cannot open unless the outlet valve is first seated, and the piston has descended sufficiently to cause the inlet valve to open and permit the entrance of gas to the cylinder. So long as the pressure within the equilibrium chamber and cylinder exceeds a certain amount, the outlet valve will remain unseated, the 20 descent of the piston not reducing the pressure sufficiently to permit the outlet valve to seat, and the inlet valve to open, and admit fresh gas. The device acts as a safety valve, and prevents excessive pressure within 25 the cylinder, equilibrium chamber and passages within which the compressed gas is carried. After reaching the point where the outlet valve remains unseated, no fresh gas will be admitted and the pressure will remain constant. The degree of pressure produced 30 by the device may be varied by changing the strength of the spring 14, and increasing or diminishing the size of the hollow rod 9 of the outlet valve. The smaller the hollow rod is, the greater will be the area of pressure within the equilibrium chamber of the outlet valve, 35 tending to seat the valve, consequently with given pressure a weaker spring 14 may be employed. This arrangement by means of which the inlet valve is carried by means of the pressure valve, permits a comparatively large size of equilibrium surface of the pressure 40 valve, thereby allowing of a weaker seating spring. By mounting the inlet valve in the pressure valve, and passing the latter through an opening which is guarded by means of a gland and rings, as described, a very simple and inexpensive type of packing is produced, such 45 packing being analogous to shaft packing, as distinguished from piston packing, which cannot be set up with a gland.

Having now described my invention, what I claim as new and desire to secure by Letters Patent is:

- 50 1. In a fluid compressor, the combination with a valve casing which contains a valve seat, and an equilibrium chamber, of a duplex valve comprising an outlet valve and an inlet valve carried thereby, the outlet valve having a stem part of hollow rod form, which passes through a wall of the equilibrium chamber, the exterior diameter of such stem part being well within the diameter of the outlet valve, the bore of the stem part constituting the

inlet passage for the gas, and being substantially coincident with the center of the valve.

2. In a fluid compressor, the combination with a valve 60 casing which contains a valve seat and an equilibrium chamber, of a duplex valve comprising an outlet valve and an inlet valve carried thereby, the outlet valve having a stem part of hollow-rod form which passes through a wall of the equilibrium chamber, the stem of the inlet valve being in line with a portion of the bore of the stem part of the outlet valve, the exterior diameter of such stem part being well within the diameter of the outlet valve, and the bore of the stem part constituting the inlet passage for the gas.

3. In a fluid compressor, the combination with a valve 65 casing which contains a valve seat, and an equilibrium chamber, of a duplex valve comprising an outlet valve and an inlet valve carried thereby, the outlet valve having a stem part of hollow-rod form which passes through a wall of the equilibrium chamber, the exterior diameter of such stem part being well within the diameter of the outlet valve, the bore of the stem part constituting the inlet passage for the gas, and a seating spring within the equilibrium chamber and surrounding the stem of the outlet 70 valve.

4. In a fluid compressor, the combination with a valve 75 casing which contains a valve seat and an equilibrium chamber, of a duplex valve comprising an outlet valve and an inlet valve carried thereby, the outlet valve having a stem part of hollow-rod form which passes through a wall of the equilibrium chamber, and the outlet valve fitting the walls of the equilibrium chamber, there being a draw-off passage in the face of the valve and adjacent to the seat thereof.

5. In a fluid compressor, the combination with a valve 80 casing which contains a valve seat and an equilibrium chamber, of a duplex valve comprising an outlet valve and an inlet valve carried thereby, the outlet valve having a stem part of hollow-rod form which passes through a wall of the equilibrium chamber and having a central bore which constitutes an inlet passage for the gas, rod packing and a gland surrounding the rod at the place where it passes through the walls of the equilibrium chamber.

6. In a fluid compressor, the combination with a valve 85 casing, which contains a valve seat and an equilibrium chamber, of a duplex valve comprising an outlet valve and an inlet valve carried thereby, the outlet valve having a hollow rod which extends through an opening in a wall of the equilibrium chamber, the bore of the rod being centrally arranged and constituting the gas inlet passage, the inlet valve having a stem part which is in line with the bore, and extends outside of the equilibrium chamber, and a spring for closing the inlet valve, and means outside of the chamber for adjusting the tension of the spring.

7. In a fluid compressor, the combination with an open-ended cylinder having a valve seat intermediate the ends, a cover-plate for inclosing the end of the cylinder, and a duplex valve having a hollow rod passing through the cover-plate, and a seating spring surrounding the rod, the bore of the rod constituting the gas inlet passage, and being centrally arranged, the said valve depending from the cover-plate and extending into the cylinder so that the valve may be removed with the cover-plate.

This specification signed and witnessed this 27th day of December, 1904.
